CLAIM

The ornamental design for a storage bag as shown and described.

DESCRIPTION

FIG. 1 is a perspective view of a storage bag showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the drawings shown in broken lines represent stitching, which does form part of the claimed design.
